ATTACHMENT TO ENABLE BOTTLES TO BE USED AS JUGS

Filed Sept. 20, 1923

UNITED STATES PATENT OFFICE.

THOMAS PETER EUSTEDE, OF WELLINGTON, NEW ZEALAND.

ATTACHMENT TO ENABLE BOTTLES TO BE USED AS JUGS.

Application filed September 20, 1923. Serial No. 663,775.

To all whom it may concern:

Be it known that I, THOMAS PETER EUSTEDE, a subject of the King of Great Britain and Ireland, residing in Wellington, in the 5 Dominion of New Zealand, have invented a new and useful Improvement in Attachments to Enable Bottles to be Used as Jugs; and I do hereby declare the following to be a full, clear, and exact description of the 10 same.

My invention relates to devices for attachment to bottles, and preferably milk bottles enabling such bottles to be used as jugs.

According to the present invention, I provide an upper portion to fit on or within the neck of the bottle and having downwardly depending members from such upper portion lying upon the exterior of the bottle, and adapted to engage beneath an exterior portion 20 of the bottle, and means whereby such members are engaged beneath and retained in engagement with such exterior portion of the bottle.

The invention is illustrated in the accompanying drawing, wherein:

Figure 1 is an elevation of the device in position upon a bottle.

Figure 2 is a sectional plan on line A—A, Figure 1.

Figure 3 is a sectional elevation of the upper portion of the device in position upon the neck of a bottle.

Figure 4 is a view of a detail.

Figure 5 is an elevation of a detail.

Figure 6 is a perspective view of the detail shown in Figure 5.

Figure 7 is an elevation of a modified form of holder in position upon a bottle.

Figure 8 is a view of a detail.

According to the drawing, the device consists of a metal frame formed of a cupped portion 1 provided with a reduced lower edge 2 to enter the neck 3 of the bottle. This cupped portion is provided with a spout 4 and, if desired, with ventilating holes 5, as in Figure 7. The lid 6 is pivoted to one side of the portion 1 by means of lugs 7 formed upon the portion 1. The lid 6 may have tongues 8 bent downwardly 50 whereby it is pivoted in the lugs 7 (see Figure 4). The lid is also provided with a handle 9 so that it may be raised by means of the thumb.

In the form shown in Figure 7, the downwardly depending members are formed of strips 10 and 11 of metal fixed to the portion

1 diametrically opposite each other and depend downwardly against the wall of the bottle, as shown in Figure 7. One of such strips 11 is formed into a handle and both 60 the strips are attached to a ring 12 surrounding the bottle. From this ring downwardly projecting legs 13 are fixed the strips forming two of such legs, while two shorter legs may be added, as shown in the drawing. 65 The bottom of each leg is formed with a foot 14. These legs are made of metal and are bent outwardly, as shown in dotted lines, so that the feet 14 will be just clear of the sides of the bottle. A loose ring 15 is located 70 around these legs adapted to be moved up or down as desired. When the ring is in its raised position the legs will be clear of the bottle, but when the ring is pushed down the legs are closed inwardly and the feet 14 75 engaged beneath the bottom of the bottle.

It will be noticed in Figure 8 that the bottom of the bottles are usually formed with a sloping inward surface and as the feet engage upon this sloping surface the ring 15, 80 as it is pushed down will draw the portion 2 into the neck of the bottle and thus secure the device firmly in position.

Projections 17 on the feet 14 limit the downward movement of the ring 15, and 85 such ring may have projections 18 to enable it to be easily operated by the fingers.

The metal strips and rings are shown flat in the drawing, but they may be of any desired shape. 90

In Figures 1 to 4, instead of the strips 10 and 11 extending to the full depth of the bottom, the strip 11 lies along the exterior of the neck of the bottle in the same way as the strip 10, and is then turned upwardly to 95 form the handle and has its ends fixed together and pivoted in the lugs 7. The strip 10 is pivoted to the portion 1 in the lugs 20. The strip 10 extends only partly down the bottle and has the loose ring 15 located upon the outside of the strips 10 and 11. Projections 21 upon the lower end of the strip 10 and the curve upon the strip 11 where the handle commences, limit the downward movement of the ring. The strip 10 may be 100 formed with arms 22 and the portion 23 below the arms curved to the contour of the bottle, so that the edge 24 fits beneath the bead 25 on the bottle, as indicated in Figure 1. In this case the strip 10 is pivoted to the 105 lugs 26 by the arms 22. The lower end of the strip 10 may also be curved at 27 to fit

partially around the bottle. More than two strips may be used if desired.

In the case of the bottle shown in Figure 7, to place the handle in position, all that is necessary is to drop the frame over the neck of the bottle and press down the loose ring 15 and the feet 14 will engage beneath the bottom of the bottle and will draw the portion 1 of the device tightly upon the neck of the bottle.

To place the device shown in Figure 1 in position, the frame is dropped over the neck of the bottle and the loose ring 15 may then be pressed downwards and the strips 10 and 11 will engage beneath the bead 25 and so secure the device to the bottle. Projections 27 upon the outer side of the strips above the projections 21 tend to prevent the loose ring from riding upwards, but does not prevent the ring being raised by hand when required.

The device shown in Figure 7 is only applicable to bottles of sizes for which the device is made, while the device shown in Figure 1 is applicable to all bottles having the standard size of neck.

Ventilating holes 28 may be formed in the cupped portion.

What I claim is:

1. In a bottle attachment, a spout portion having a reduced neck to fit within the neck of the bottle, downwardly depending members from such spout portion adapted to lie upon the exterior of the bottle and to engage beneath an exterior portion thereof, and a loose ring encircling said members so as to engage said members beneath and retain them in engagement with the said exterior portion of the bottle.

2. In a bottle attachment, a spout portion

to fit on or within the neck of a bottle, downwardly depending members from said spout portion adapted to lie upon the exterior of the bottle, downwardly projecting spring legs forming part of said members and having feet to engage beneath the bottom of the bottle, and a loose ring encircling the said legs so as to retain the said feet.

3. In a bottle attachment, a spout portion to fit on or within the neck of a bottle, downwardly depending members from such spout portion adapted to lie upon the exterior of the bottle and to engage beneath an exterior portion thereof, a loose ring encircling said members so as to engage them beneath and retain them in engagement with such exterior portion of the bottle, one of said downwardly depending members being formed into a handle.

4. In a bottle attachment, a spout portion to fit on or within the neck of a bottle, downwardly depending members from such spout portion adapted to lie upon the exterior of the bottle and to engage beneath the bead upon the neck of the bottle, said downwardly depending members being formed with a curved portion to engage around and beneath the bead of the bottle, said members being pivoted to the spout portions engaging the top of the bottle, and a loose ring encircling said members so as to retain them beneath the said bead.

In testimony whereof, I have signed my name to this specification in the presence of two subscribing witnesses.

THOMAS PETER EUSTEGER.
